VANITY CASE

Filed Dec. 24, 1927

Inventor
Philip A Reutter
By his Attorney
Philip Savoy Ric Keen

UNITED STATES PATENT OFFICE

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT

VANITY CASE

Application filed December 24, 1927. Serial No. 242,307.

This invention relates to certain improvements in vanity boxes or cases, and particularly to vanity boxes or cases capacitated to carry a cosmetic in powder form.

5 These small boxes or cases are now largely used for carrying cosmetics. To produce a saleable article, these boxes should be of attractive and novel appearance, and in boxes intended to carry the cosmetic in powder form 10 the boxes should be constructed so as to be practically proof against accidental leakage of loose powder. The boxes furthermore should be capacitated to conveniently carry a puff or similar applicator and a mirror arranged conveniently for use.

15 It is the special object of the present invention to provide a vanity box of novel form and arrangement which is attractive in appearance, and in which there is provided a 20 compartment for holding loose powder, the box being constructed so as to be practically proof against accidental leakage of the powder. As to certain features of the box, this 25 special object is carried out by providing a container of a shape generally resembling a watch case, the powder being distributed through the stem of the watch case.

It is a further object of the invention to 30 produce such a loose powder container in which an improved means is provided for rendering the box proof against leakage of powder, and in which convenient provision is made for carrying an applicator and a 35 mirror.

With these and other objects not specifically 40 referred to in view, the invention consists in certain novel parts, arrangements and combinations which will be described in connection with the accompanying drawings and the novel features pointed out in the claims hereunto appended.

In these drawings,—

Figure 1 is a top or plan view of the im- 45 proved box;

Figure 2 is an end view or edge view showing the parts closed against the distribution of powder;

Figure 3 is a view similar to Figure 2 showing the powder distributor open;

Figure 4 is a view similar to Figure 1 showing the box open, and

Figure 5 is a detail sectional view on an enlarged scale showing the construction of the box, the view being taken on line 5—5 of 55 Figure 1.

Referring now to these drawings, to provide a box of novel and attractive appearance, there is shown a box or case which is generally in the shape of a watch case. While 60 such shape forms one of the important features of the invention, it will be understood that as to certain other features the invention is not to be restricted to this form of box but that other forms may be used, as will herein- 65 after appear.

In the construction shown, however, there is provided a box having a body 1 which forms a compartment 2 adapted to contain loose powder, indicated at 3. This box is, as 70 shown in Figures 2 and 3, a thin box circular in form and shaped substantially like a watch case. The body of the box is provided with a lateral hollow stem 4 terminating in a head 5 provided with distributing orifices 6. This 75 head is closed by a movable member having distributing orifices 7, this member being in the form of a cap 8 having a skirt or flange 9, which is bent in under the head 5 to rotatably engage the stem 4. A stop, as a pro- 80 jection 10 formed on the head, may be provided, this stop working in a slot 11, shown in Figure 2, for limiting the rotary movement of the cap in either direction.

With the construction so far described, the 8 powder is dispensed from the chamber by rotating the cap to the position shown in Figure 3, whereupon powder may be discharged through the stem by shaking the box, and a box simulating a watch case has 85 been provided of novel and attractive appearance. In boxes of the type shown, means are provided for sealing the powder compartment so as to prevent accidental leakage of powder, and convenient provision is made 90 for carrying an applicator and a mirror, and such means are applicable to the watch case type box, but may be used with boxes having other shapes.

In the construction illustrated, the cham- 100

ber 2 is provided with a rather wide inwardly turned flange or rim 12, shown in Figures 1 and 4. This rim is formed at its inner edge with a depending flange 13, which terminates in an inwardly extending shelf or shoulder 14, from which depends a short vertical flange 15. Supported on the shoulder 14 is a shallow tray having a bottom 16, a short vertical flange 17 and a horizontal flange 18, the flanges 17 and 15 having a close friction fit, so that the tray acts as a closure for the powder compartment, which effectually prevents leakage of powder therefrom. This tray is capacitated to carry a suitable applicator in the form of a puff 19. The box is closed by a lid, indicated at 20, and in the particular construction shown this lid is arranged to carry a suitable reflecting medium, as a mirror 21, the mirror being held in place in the lid by a bezel 22, this bezel having a frictional engagement with a flange or collar 23 depending from the lid. The parts are so proportioned that the collar 23 has a close frictional engagement with the inner wall of the flange 17, the rim 24 of the lid seating on the flange 18 of the tray. Thus the lid is seated when closed within the flange 12 of the box, so that the thin appearance of the structure is maintained. The lid 20 is preferably pivotally associated with the box by means of a hinged strap 25 and a pintle 26. If desired, a depression, indicated at 27, may be formed in the rim 12 of the box to provide for ready removal of the tray, the tray being provided with an upstruck portion 28. Similarly, a depression 29 may be provided for permitting the ready lifting of the lid 20, this lid being provided with an upstruck portion 30.

With the construction shown and described, it will be clear that a box of novel form has been provided and one in which loose powder may be confined against accidental leakage and may at the same time be readily dispensed for use.

While the invention has been shown and described in its preferred form and arrangement of the parts, it will be understood that certain changes and variations may be made in the structure shown and described without departing from the invention, and as to certain features the invention may be used with containers or boxes other than those of a watch case form.

What I claim is:

1. A vanity box or case comprising a relatively thin circular loose powder containing shell provided with a laterally extending stem terminating in an enlarged head, a passage through the stem and connecting with the shell for the passage of powder therefrom, powder dispensing orifices in the head, means for opening and closing the orifices, a puff holding tray in the container shell, and a hinged cover smaller than the

case over the tray and having a flange arranged for close frictional engagement with the inner wall of the tray.

2. A vanity box or case comprising a shell forming a loose powder compartment and having means for dispensing loose powder therefrom, an integral inwardly extending rim around the edge of the shell, a flange depending from the rim, an inset part integral with and extending inwardly from the flange, a vertical flange depending from the inset, a tray having a rim seating on the first flange and an inset vertical flange having a close friction fit with the second flange, and a cover over the tray and provided with a flange having a friction fit with the vertical flange of the tray.

In testimony whereof, I have hereunto set my hand.

PHILIP A. REUTTER.
